Primary Examiner — Austin Murphy(74) *Attorney, Agent, or Firm* — Zagorin Cave LLP; Robert W. Holland(57) **CLAIM**

We claim the ornamental design for a information handling system mouse, as shown and described herein.

DESCRIPTION

FIG. 1 is a front perspective view of the information handling system mouse comprising the present invention; FIG. 2 is a front elevation view thereof; FIG. 3 is a rear elevation view thereof; FIG. 4 is a right side view thereof; FIG. 5 is a left side view thereof; FIG. 6 is a top view thereof; FIG. 7 is a bottom view thereof; and, FIG. 8 is a rear perspective view of an alternative embodiment of the information handling system mouse. Broken lines shown in the drawings illustrate portions of the information handling system mouse, and form no part of the claimed design.
